UNITED STATES PATENT OFFICE.

CHARLES ROGERS, OF ALLEGHENY, ASSIGNOR OF ONE-HALF TO ISAAC VANCE
AND T. I. VANDERGRIFT, OF PITTSBURG, PENNSYLVANIA.

PRESSURE-REGULATOR.

SPECIFICATION forming part of Letters Patent No. 398,849, dated March 5, 1889.

Application filed July 9, 1888. Serial No. 279,447. (No model.)

To all whom it may concern:

Be it known that I, CHARLES ROGERS, a citizen of the United States, residing at Allegheny, in the county of Allegheny and State of Pennsylvania, have invented certain new and useful Improvements in Pressure - Regulators; and I do hereby declare the following to be a full, clear, and exact description of the invention, such as will enable others skilled in the art to which it pertains to make and use the same, reference being had to the accompanying drawings, which form a part of this specification.

My invention relates to an improvement in pressure-regulators, the object being to provide an apparatus whereby gas or other substance may be reduced from a high to a low or moderate pressure, and at the same time prevent what is known to the art as "knocking," or, in other words, to provide a device that when in operation will be noiseless.

With these ends in view my invention consists of the combination, construction, and arrangement of parts, as will be hereinafter fully described, and particularly pointed out in the claims.

In the accompanying drawings, Figure 1 is a side sectional elevation of my improved pressure-regulator constructed in accordance with my invention. Fig. 2 is a plan view of the same, having the cap or cover removed therefrom the better to show the inner working parts. Fig. 3 is a transverse sectional elevation of the apparatus, taken through the high and low pressure chambers. Fig. 4 is a side elevation of the valve. Fig. 5 is an inverted plan view of the same.

To put my invention into practice, I provide a metallic box, *a*, of suitable size and form of construction, having formed in one end thereof two chambers, *b* *c*, separated the one from the other by a partition-wall, *d*, which by its peculiar shape forms a bench, and is used as a valve-seat, *e*, for a valve, *f*, which divides or separates the high-pressure chamber *c* from the low or moderate pressure chamber *b*. This valve *f* is provided with a number of downwardly-extending arms or guides, *g*, connected at the top to the valve *f* in the form of a *V*, as will be seen by reference to Figs. 4 and 5 on the drawings. These *V*-shaped grooves *i* admit the gas gradually and slowly

from the chamber *c* to the low-pressure chamber *b* upon the slightest movement of the valve *f*, therefore preventing any quick or abrupt movement of the parts connected therewith. Above this valve *f* is a small spherical-shaped chamber, *i'*, in direct communication with the high-pressure chamber *c* by means of a small channel, *j*, formed in the casting *o*, and entering the said chamber *i'* near the top. Operating at the base of this spherical-shaped chamber *i'* is a balancing plunger or plug, *k*, connected to the valve *f* below by a stem, *l*, and rendered gas-tight by means of a flexible rubber or leather disk, *n*, securely attached to the top of the balancing plunger or plug *k*. This plunger *k* acts as a balance to the valve *f*, separating the high and low pressure chambers *c* *b*.

Between the top of the low-pressure chamber *b* and the casting *o*, having the spherical chamber *i'* formed therein, is a flexible diaphragm, *m*, properly secured to the connecting valve-stem *l*, which prevents any leakage from the chamber *b* at that point and counteracts the atmospheric pressure on the base of the balancing plunger or plug *k*. The top of the spherical chamber *i'* is provided with a screw-cap, *p*, which is used for properly placing the valves and their connected portions in position.

At a suitable point in the top wall of the low-pressure chamber *b* a relief-valve, *q*, is placed, which is provided with a weight, *r*, and adapted to allow the gas to escape from that chamber *b* should any of the several parts of the regulator become deranged, and thereby relieve the same from excessive pressure. To one side of these two chambers *b* *c* is arranged a large diaphragm, *s*, having attached thereto a connecting-piece, *t*, which is attached to a horizontal lever, *u*, one end of which is attached to a boss, *v*, formed on the valve-stem *l*. This lever *u* is provided with a moving weight, *w*, capable of being moved toward and away from the fulcrum or bearing post *y*, and secured in any position by a small set-screw, *x*, set in overhanging lugs of the weight *w*. A small channel, *z*, connects the low-pressure chamber *b* with the space A beneath the large diaphragm *s*. Surrounding the above-described apparatus is a cap or cover, *B*, which confines any escaping gas,

which is carried to a point of safety through a pipe, D, entering the space formed by the cover.

In operation the gas is introduced into the 5 high-pressure chamber c through a pipe, F, entering the same, and by the working of the valve f passes out of the low-pressure chamber b through the pipe G at a low or moderate pressure. The valve f and the plunger or 10 plug k, connected thereto, are accurately balanced, so that the pressure of gas in the chamber c moves the same vertically off their seats, and in so doing the gas is admitted into the low-pressure chamber b through the V-shaped 15 openings i of the valve f. The gas thus entering the said chamber b escapes into the space A below the large diaphragm s through the channel z. This large diaphragm s, when the pressure beneath the same equals the de- 20 sired pressure in the chamber b, moves upward, thereby operating the lever u to close the lower valve, f, until such times as a portion of the gas has been carried and used through the service-pipe.

25 It will be seen that the construction of the valve f, separating the high and low pressure chambers b c, is such that a quick or abrupt movement of the same is rendered impossible. The gas gradually and slowly es- 30 caping from the V-shaped grooves i into the low-pressure chamber b fills the same and gives the large diaphragm s ample time to operate to close the valve f, thereby avoiding what is commonly known in this class 35 of apparatus for regulating fluid-pressure as "knocking."

Having thus described my invention, what I claim, and desire to secure by Letters Patent, is—

40 1. In a pressure-regulator, the high and low pressure chambers b c, separated by a wall or bench, d, having a valve-seat, a valve, f, fitted on said valve-seat, a separate chamber, i, communicating with the high-pressure chamber, 45 another separate chamber, A, communicating with the low-pressure chamber, a balancing plunger or plug, k, operating in the chamber i and connected with the valve f, and a dia- 50 phragm in the chamber A, and having inter- 55 mediate connections with the valve-stem, sub- 60 stantially as and for the purpose described.

2. In a pressure-regulator, the high-pressure chambers c i, communicating with one another through an intermediate contracted 55 passage, o, the low-pressure chambers b A, also communicating with one another through a separate passage, z, a valve, f, for establishing communication between the high and low pressure chambers b c, a balancing plug or 60 plunger, k, in the high-pressure chamber i, connected with the valve, and a flexible dia- phragm in the low-pressure chamber A, and connected by an adjustably-weighted lever with said valve, substantially as and for the 65 purpose described.

3. In a pressure-regulator, the combination of the high and low pressure chambers b c, another elevated chamber, i, communicating with the low-pressure chamber, a valve, f, for establishing communication between the high 70 and low pressure chambers, a balancing plunger or plug operating in the chamber i and connected to the valve-stem, and a diaphragm located in the upper part of the low-pressure chamber and connected with the valve-stem, 75 substantially as and for the purpose de- 80 scribed.

4. In an apparatus for the purpose set forth, the combination consisting of the valve f, having V-shaped openings i formed below the seat 85 of the same, the balance plunger or plug k, connected thereto and operating at the base of a spherical chamber, i', the flexible disk n, se- 90 cured to the top of the plunger or plug k, the passage j, connecting the high-pressure cham- 95 ber c with the said spherical chamber i', and the diaphragm m, properly attached to the valve-stem l, whereby a gas-tight connection is made and an atmospheric balance is formed, as and for the purpose described. 90

5. In a pressure-regulator, the combination of the high and low pressure chambers b c, a valve, f, for establishing communication between said chambers, another elevated chamber, i, communicating with the high- 95 pressure chamber, a plunger or plug operating in the chamber i and connected to the valve-stem to move with the valve, and a flexible disk, n, secured to the plunger or plug and extending at its edges beyond the 100 plunger or plug to bear against the wall of said chamber i, substantially as described.

6. An apparatus for the purpose described, consisting of the valve f, provided with V-shaped openings i below the seat h, the bal- 105 ance plunger or plug k, connected thereto, the spherical chamber i' and disk n, secured to the top of the balance-valve k, the pas- 110 sage j, leading from the high-pressure cham- 115 ber c to that above the balance plunger or plug k, the small diaphragm m, attached to the valve-stem l, the high and low pressure chambers b c, the relief-valve q, the large diaphragm s, having a passage, z, communi- 120 cating with the low-pressure chamber b and the space beneath the same, and the weighted lever u, connected to the diaphragm s and to the valve-stem l, having an intermediate post or bearing, y, between the same, substan- tially as described.

In testimony that I claim the foregoing I hereunto affix my signature this 6th day of June, A. D. 1888.

CHARLES ROGERS. [L. S.]

In presence of—

C. C. LEE,

M. E. HARRISON.
